United States Patent Office.

JONATHAN CRABTREE, OF PHILADELPHIA, PENNSYLVANIA, ASSIGNOR TO
WILLIAM HOGG, JR., OF SAME PLACE.

Design No. 3,837, dated February 8, 1870.

DESIGN FOR A CARPET-PATTERN.

The Schedule referred to in these Letters Patent and making part of the same.

I, JONATHAN CRABTREE, of Philadelphia, county of Philadelphia, State of Pennsylvania, have invented a Design for a Carpet-Pattern, of which the following is a specification.

The accompanying drawing represents sufficient of a carpet-pattern to illustrate the design, the latter consisting mainly of the six-sided figures A A¹ A², &c., arranged at equal distances apart, and connected together by bars *a a*, which cross each other at right angles.

At the intersection of the bars *a a* is a square or diamond-shaped spot, *b*, and at the junction of each of the said bars with the main figures A A¹, &c., are similar but somewhat smaller spots, *c*.

An ornamental border or fringing, *d*, extends entirely around the figures A and their connecting-bars *a*, and the interiors of the latter, as well as of the said figures, are ornamented, as shown.

The ground-work of the pattern in the spaces which intervene between the several figures A A¹ A², &c., is alternately light and dark, and in these spaces are arranged figures B, B¹, B², and B³, of the peculiar form and ornamentation clearly represented in the drawing.

Irrespective of the colors employed,

I claim the design for a carpet-pattern, substantially as described and as represented in and by the accompanying drawing.

In testimony whereof, I have signed my name to this specification in the presence of two subscribing witnesses.

JONATHAN CRABTREE.
